LATCH FOR CASKETS

Donald A. Morand, Portland, Oreg., assignor to
East Side Tool & Die Works, a corporation of
Oregon

Application December 10, 1951, Serial No. 260,790

1 Claim. (Cl. 292—1)

1

This invention relates generally to hardware and particularly to a latch for caskets.

The main object of this invention is the provision of an inexpensive latch which is easy to apply and which will not weaken the rim structure of the casket.

The second object is to so construct the latch that it will not project laterally from the casket, thereby avoiding the danger of being unintentionally operated or rendered inoperative by striking another object.

A further object is to construct a simple, positive sealing casket fastener which will seal its opening into the lower portion of the casket shell, thereby accomplishing two purposes and eliminating much work in installation and also furnishing a sealing fastener and a positive fastener in one item.

These and other objects are accomplished in the manner set forth in the following specifications as illustrated in the accompanying drawing, in which

Fig. 1 is a perspective view of the casket showing the latch applied thereto.

Fig. 2 is a fragmentary section taken along the line 2—2 in Fig. 1, showing the latch applied to a casket viewing door of hollow metal construction.

Fig. 3 is an exploded view showing the component parts.

Fig. 4 is a view similar to Fig. 2 showing the latch applied to a viewing door of wooden construction.

Fig. 5 is a section taken along the line 5—5 in Fig. 4.

Like numbers of reference refer to the same or similar parts throughout the several views.

Referring in detail to the drawing, there is shown a common form of casket 10 having a cover or lid 11 which is hinged and otherwise secured in place. On the lid 11 is shown the so-called "viewing door" 12 mounted on the elongated hinge 13.

The latch about to be described is especially adapted for use in holding the door 12 closed, although it can be used for other purposes such as holding the main cover 11, if desired.

The latch itself is comprised of several members. An elongated screw 14 having a knurled head 15 is rotatably mounted in the face plate 16 having a boss 17 formed thereon whose face 18 engages the knurled screw head 15 and whose face 19 is held against the door 12 by screws (not shown) which extend through the holes 20 in the plate 16.

The face 18 is inclined with relation to the 55

2

outer surface of the door 12, so that the face 18 will be parallel to the door side 21 which engages the frame 22 around the door opening 23.

In Fig. 2, the frame 22 has a large circular opening 24 concentric with the screw 14. The frame 22 has an inturned flange 25. The outer side of the door 12 and the door side 21 are provided with holes 26 and 27 for the screw 14. The hole 24 is much larger in diameter than the hole 27.

On the screw 14 is placed a resilient cylindrical washer 29 which, when not compressed, can pass freely through the hole 24. On the end of the screw 14 is placed a nut 30 having a somewhat rounded end 31 and the rim 32 on its rubber engaging end 33. The friction between the members 21, 29 and 30 is sufficient to hold the nut 30 against rotation while the screw 14 is being turned.

When the nut 15 is tightened, the compression of the washer 29 completely closes the hole 27 and seals the opening against the admission of moisture or the escape of gases.

In the form shown in Fig. 4, there is added a plate 34 which is held in place on the wooden frame 35 by the screws 36. The hole 37 is the same in size as is the hole 28 shown in Fig. 2. In Fig. 4, the hole 37 is carried on through the frame 35.

The operation of the latch can be best understood by a comparison of Figs. 2 and 4. In Fig. 4 the washer 29 is not under compression and passes freely through the hole 37 in the plate 34, which is the same diameter as the hole 28 in the frame 22. When the screw 14 is turned into the nut 30, the washer 29 is placed in compression and expanded as shown in Fig. 2, so that the washer 29 cannot pass through the hole 28 or 37, locking the door 12 securely in place. Obviously a reversal of the screw 14 will release the latch.

It can be seen from the foregoing that all difficult fitting is eliminated and that a drill and screwdriver are the only tools required to install my latch and its proper installation is easily accomplished. The latch also acts as a positive holder of the door 12 against any side movement on its hinge 13.

I claim:

A latch for securing a casket lid to a casket body comprising a face plate having means for attaching it to the sloping top of a casket lid, said plate having a boss formed thereon, the top of which is in a substantially horizontal plane, said boss having a vertical hole formed therethrough, a screw having one end threaded and

having the other end headed and journaling in said boss, a cylindrical rubber washer on the threaded portion of said screw and a bullet-shaped nut on said screw less in diameter than is said washer and having its rubber engaging end concave.
